UNITED STATES PATENT OFFICE.

ALBERT A. GORDON, JR., OF WORCESTER, MASSACHUSETTS, ASSIGNOR TO CROMPTON & KNOWLES LOOM WORKS, A CORPORATION OF MASSACHUSETTS.

SHEDDING MECHANISM FOR LOOMS.

1,060,977.

Specification of Letters Patent.

Patented May 6, 1913.

Application filed June 22, 1911. Serial No. 634,735.

To all whom it may concern:

Be it known that I, ALBERT A. GORDON, Jr., a citizen of the United States, residing at Worcester, in the county of Worcester 5 and State of Massachusetts, have invented certain new and useful Improvements in Shedding Mechanism for Looms, of which the following is a specification.

My invention relates to shedding mechanism for looms, and more particularly to an auxiliary mechanism for weaving letters, names, trade-marks, etc., on the border or other portion of the fabric, to be used on looms in addition to and in connection with 15 the ordinary shedding mechanism.

The object of my invention is to provide a mechanism of the class referred to of improved construction, to be used on a loom as an auxiliary shedding mechanism.

20 My improved mechanism is preferably located on the opposite end of the loom from the harness operating mechanism, and is adapted to operate a certain number of warp threads on the border, or some other 25 part of the fabric, to weave letters, names, trade-marks, or other designs, into the fabric, according to a pattern indicating card, or chain, of wooden bars provided with pegs, in the usual way.

30 In my auxiliary shedding mechanism I pivot on the lower part of the harness levers of a dobby, of the type shown in Patent, No. 720,896, jack levers having at their outer ends means to attach harnesses, and 35 at their inner ends, on the opposite side of their fulcra, surfaces contacting with a stationary abutment on the frame of the dobby, said abutment comprising preferably a rod supported in one of a series of holes in said 40 frame which holes are arranged radially relative to the pivot of the jack lever. Any other form of abutment may be used if preferred. The sheds by this construction may be easily varied, by moving said rod out or 45 in relative to the pivot point of the jack lever, and by moving one end of the rod farther than the other end, an incline may be made in the shed. By the use of these jack levers, a harness for weaving the name, 50 can be readily adjusted to accommodate different characters of weave, and different tensions, and also carry all of the warp threads on the back of the fabric when desired, without in any way changing the more

difficult setting or adjusting of the dobby 55 itself.

My invention consists in certain novel features of construction of my improvements, as will be hereinafter fully described.

I have only shown in the drawings my 60 improved mechanism, detached, with sufficient parts of a loom combined therewith, to enable those skilled in the art to understand the construction and operation thereof.

Referring to the drawings:—Figure 1 is 65 a front view of a dobby with my improvements applied thereto, looking in the direction of arrow *a*, Fig. 3. Fig. 2 shows the opposite side of the parts shown in Fig. 1, looking in the direction of arrow *b*, Fig. 70 3, some of the parts shown in Fig. 1 are not shown in this figure, and some parts are shown in section. Fig. 3 is an outside end view of the parts shown in Fig. 1, looking in the direction of arrow *c*, same figure. Fig. 75 4 shows some of the parts shown at the right in Fig. 1, detached, and in a different position, and, Fig. 5 corresponds to Fig. 4, but shows the parts shown in Fig. 4 in a different position.

In the accompanying drawings, 1 is a portion 80 of the loom arch at the front of the loom, 2 is a portion of the loom arch at the rear of the loom. The arch 2 has secured thereto a bracket 3, on which is mounted 85 the frame 4 of the dobby: only one frame 4 is used in this instance. The opposite frame consists of a bracket 5, see Fig. 2, and the stand 5', on which are supported the several parts of the dobby mechanism. The harness 90 operating mechanism consists in this instance of the levers 6, pivotally supported on their hubs on a rod 7. The levers 6, in this instance twelve in number, have pivotally mounted thereon, on studs 8 carried 95 on said levers 6, the hubs 9' of the jack levers 9, see Fig. 1. The jack levers 9 extend toward the front of the loom, and have their ends provided with harness cords 10, which pass through a guide plate 11 on 100 a stand 12, and downwardly through a small combler board 13, suitably located over the place where the border or edge is to be woven on the fabric.

Extending rearwardly from the hubs 9' of 105 the jack levers 9, is in this instance an arm or projection 9'', see Fig. 1, which is adapted to bear against an abutment, in this in-

stance a transverse stationary bar or rod 14, located on the lower part of a frame 15 secured to the dobby frame 4. The rod 14 can be located in one of a plurality of holes 15' in the lower end of the frame 15, and acts in this instance to increase the throw of the jack levers 9, to form a full sized shed in the warps for the passage of a shuttle. One end of the rod 14 can be placed in one of the holes 15', as the one the farthest from the pivot 8 on the front frame, and the other end of the rod can be placed in the hole nearest the pivot on the back frame, which will act to increase the throw of the end of the jack levers for the back harness, and that of the jack levers for the front harness, thereby forming a desirable incline to the warp threads of the shed.

On the upwardly extending projection 6' on the lever 6, see Fig. 2, is centrally pivoted the hook lever 16; to the upper and lower ends of each hook lever 16 is pivotally attached the end of a hook 17 and 18, respectively, in the ordinary way. The upper hooks 17 are raised, through wires 19 operated by the dobby fingers 20, and the lower hooks 18 are raised by the dobby fingers 21, to disengage their hook ends from the upper and lower lifter bars 22 and 22', respectively. The fixed abutments engage one end of a hook lever, as its opposite end is moved outwardly by a lifter bar. The hubs of the dobby fingers 20 and 21 are pivotally mounted on a rod 23, and said fingers extend outwardly above a pattern cylinder 24, mounted on a shaft 25; said cylinder 24 carries in this instance the pattern chain, made up of a series of bars linked together, and carrying pattern pins in the usual way. Only one bar 26 is shown in Fig. 2, with an indicating pin 27 thereon.

The lifter bars 22 and 22', form a frame, with its arms 22'' extending out from the hubs 22''', which are loosely mounted on a shaft or rod 29, see Fig. 3. The outer hub 22''' of the lifter bars 22 and 22', has the part 30' extending out therefrom, and back to the outer hub 30'' on the lever 30, see Figs. 1 and 3. A stud 31, adjusted in an elongated opening 30* in the lever 30, see Fig. 1, has pivotally connected thereto the rod head 32 of a downwardly extending rod or connector 33; through said connector 33 a rocking motion is communicated to the lever 30 from some driven part of the loom, preferably from the bottom shaft, not shown. Extending out from the hub 30'' is an arm 30''', which is preferably forked at its end, and has a stud 34, which loosely carries the hub 35' of a downwardly extending pull pawl 35. The pawl 35 is adapted to engage and operate the ratchet wheel 36, fast on the shaft 25, to operate and rotate the pattern cylinder 24 of the dobby. The outer end of the stud 34 has pivotally mounted thereon

the hub 37' of a second pawl or push pawl 37, which is adapted to engage and operate the ratchet wheel 38 on the multiplier cylinder 39, which is loosely mounted on the cylinder shaft 25. The multiplier cylinder 39 is made in this instance in two sections 39', and 39'', see Fig. 3, each of which is adapted to carry a pattern chain 40. The chain 40 consists of links 40, and in this instance one low link 40'. The rest of the links 40 of the chain 40 are of uniform size and higher than the low link 40'. The chain 40 is adapted to operate a lever or finger 41, see Fig. 1, which has its hub 41', see Fig. 3, loosely mounted on the rod 23. An arm 42 extends upwardly from the hub 41' and has adjustably fastened thereon a bent wire or pin 43, which is adapted to engage a cam shaped projection 35* on the pull pawl 35, see Fig. 5. As long as a high link of the chain 40 comes under the finger 41, the pawl 35 will be disengaged from the ratchet wheel 36, and leave the pattern cylinder 24 at rest, as shown at Fig. 5. When a low link 40' comes under the finger 41, the wire 43 will disengage the pawl 35 and allow it to operate the pattern cylinder 34.

According to the pattern indication, the push pawl 37 is prevented from operating the multiplier cylinder 39, by a lug or projection 44' on a lever 44, see Fig. 3. The lever 44 has its hub loosely mounted on the rod 23, and has an arm extending upwardly and inwardly from the engaging end 44*, above the end of the pattern chain bars 26. A helically coiled contraction spring 45 has one end connected to an arm 41'' on the hub 41' of the finger 41, and its other end connected to the lug 44', and acts to cause both levers to be yieldingly moved to engage their respective pattern indicating chains.

As long as the lever 44 remains in the position shown in Figs. 1 and 3, the push pawl 37 is held out of engagement with the ratchet wheel 38 on the multiplier cylinder 39, by the lug or projection 44' on the lever 44, and as the finger 41 remains upon a low link 40', causes the continuous operating of the pull pawl 35 for the pattern cylinder 24 of the dobby.

The last chain bar 26 of the pattern chain is provided with an extension or lug 26*, see Figs. 4 and 5, which is adapted to engage and raise the engaging end 44* on the lever 44, and move the lug 44' on said lever away from the pawl 37, and cause said pawl 37 to engage the ratchet wheel 36, to turn the multiplier cylinder 39, and cause, through a high link 40, the finger 41 to move the pull pawl 35, and to disengage said pull pawl 35 from the ratchet wheel 36, to leave the pattern cylinder 24 at rest, until a low link 40' comes again under the finger 41, which causes the pull pawl 35 to operate the pattern cylinder 24.

To obtain a long repeat on the multiplier chain while the dobby cylinder remains at rest, I provide the multiplier cylinder 39 with two separate chains, upon the sections 5 39' and 39'', each of the chains have one low link, and the number of the links in one chain differs by one link from the number of the links in the other chain.

It will be understood that a long repeat is obtained by the differential moving of the 10 chains relative to each other, until a low link in each chain meets at the same time, at the place where the finger 41 is located, to lower said finger 41, and put into operation 15 the pattern cylinder 24 of the dobby.

The operation of my auxiliary shedding mechanism is as follows:—The main pattern chain, formed of bars 26, having a design, as a name, indicated by pegs 27 thereon, causes the harness lever 6 to be moved in the usual way by the hooks 17 and 18, moving upward the fulcrum pins 8, which carry with them the hubs 9' on the jack levers 9, the rearwardly projecting ends 9'' of 20 said levers, contacting with the fixed rod 14, and increasing the movement of the outer end of the jack lever, and raising the harness cords 10, bringing the warp threads into a full sized shed for the passage of an ordinary 25 shuttle in weaving the fabric. By placing the rod 14 in a hole 15', nearer the fulcrum pin 8, for the back lever than for the front one, the shed will be raised into an inclined position, and the warps will all be 30 in the same plane above the shuttle as it passes through.

With the dobby operating as above described, the weaving of the fabric with the letters of the name in the border proceeds, 40 until the end of the chain carrying the pegs for the name is reached, after which, if no pegs are placed on the succeeding bars of the chain, the harness cords will not be raised, and the warp threads will all remain 45 down and be carried on the back of the fabric as it is woven.

As it is desirable to continue the weaving of the fabric a long distance, usually one yard, more or less, before the name is repeated, any of the well known chain multipliers may be used to accomplish this, and the pattern cylinder will then remain at rest. The multiplier chain I prefer to use is shown 50 in Figs. 4 and 5, and consists of two separate chains of unequal length carried on a hub, and a ratchet wheel and pawl to move them simultaneously, each chain having a single indication, which may be a low link. The differential movements of the chains eventually brings a low link on each chain under the finger 41, and lowers said finger 41, and puts into operation the pattern cylinder 24 of the dobby. At the termination 55 of the weaving of the name, an indicating peg on the pattern chain, through an inter-

mediate lever, causes the pawl to engage the ratchet wheel on the hub and put the multiplier chain in motion, and the finger 41, when it is lowered by two low links coming under it, will lower the pawl into engagement with the ratchet wheel of the pattern cylinder, and put it into operation. 70

It will be understood that the details of construction of my improvements may be varied if desired. 75

I do not claim broadly the use of a multiplier chain, in connection with a dobby mechanism, but I believe that I am the first to use in an organized loom, a harness mechanism to form sheds in the warps, and an auxiliary mechanism, comprising a miniature sized dobby for weaving names in the border, having means to form full sized sheds with the name weaving warp threads, and two multiplier chains, to control the 80 pattern mechanism, to leave blank spaces between the names, whereby a maximum amount of work can be produced with a minimum amount of mechanism. 85

Having thus described my invention, what 90 I claim as new and desire to secure by Letters Patent is:—

1. In shedding mechanism for looms, a series of harness levers, and jack levers having their fulcrs on said harness levers, harness connections from said jack levers, a rod or bar to be engaged by the inner ends of the jack levers, and adjustable with reference to the fulcrums of the jack levers, whereby the shed formed by the movement 95 of the jack levers may be increased or diminished. 100

2. In shedding mechanism for looms, a series of harness levers, and jack levers having their fulcrs between their ends upon 105 projections on said harness levers, harness connections from said jack levers, a rod or bar having one end in a fixed position nearer the fulcrums of said jack levers than the other end, whereby when the fulcrums are 110 moved upward to form sheds, the increased movement of the outer end of a jack lever will be at the end of said rod or bar, which is nearest the fulcrum of said jack lever.

3. In shedding mechanism for looms, the 115 combination with a dobby, having harness levers, hook levers, abutments for the ends of the hook levers, lifting hooks, and lifter bars, of jack levers for the harnesses, having their fulcrs on said harness levers, and a stationary abutment to be engaged by the inner end of said jack levers. 120

4. In shedding mechanism for looms, a harness lever, a jack lever, having its fulcrum on said harness lever, harness connections from one end of said jack lever, a stationary abutment to contact with the inner end of said jack lever, means to move said harness lever, consisting of a hook lever centrally pivoted on a projection on the harness 125 130

lever, lifting hooks, pivoted one at each end of said hook lever, outwardly moving lifter bars for the lifting hooks, and fixed abutments for each end of said hook lever, one of said abutments to engage one end of said hook lever, as its opposite end is moved outwardly.

5. The combination with a shedding mechanism for weaving names in the border of fabrics, with spaces between the names, and having harness levers, hook levers, fixed

abutments, lifting hooks, and lifter bars, and pattern indicating mechanism, of jack levers for the harnesses, having their fulcra upon the harness levers, and an adjustable abutment, by which the warps may be regulated when weaving between the names, to carry the warps on the back of the fabric. 15
